DESIGN FOR A DISPENSER CAP

John D. Becker, Chowchilla, Calif.

Application June 9, 1941, Serial No. 101,357

Term of patent 3½ years

To all whom it may concern:

Be it known that I, John D. Becker, a citizen of the United States, residing at Chowchilla, in the county of Madera and State of California, have invented a new, original, and ornamental Design for Dispenser Cap, of which the following is a specification, reference being had to the accompanying drawing, forming a part thereof, and in which:

Fig. 1 is a perspective view of a dispenser cap, showing my new design, and

Fig. 2 is a side elevational view of the same.

I claim:

The ornamental design for a dispenser cap, as shown.

JOHN D. BECKER.
